UNITED STATES PATENT OFFICE.

WILLIAM FREDERIC STEVENS, OF CHICAGO, ILLINOIS.

DESIGN FOR A SERVICE-EMBLEM.

54,362.

Specification for Design.

Patented Jan. 20, 1920.

Application filed December 16, 1918. Serial No. 267,062. Term of patent 3½ years.

To all whom it may concern:

Be it known that I, WILLIAM FREDERIC STEVENS, a citizen of the United States, residing at Chicago, in the county of Cook and State of Illinois, have invented a new, original, and ornamental Design for a Service-Emblem, of which the following is a specification, reference being had to the accompanying drawing, forming a part thereof.

The drawing is a front elevational view of

a button employed as a service emblem showing my improved design.

The design comprises a chevron upon a field of horizontal stripes of red, white and blue, as shown in the accompanying drawing.

I claim:

The ornamental design for a service emblem as shown.

WILLIAM FREDERIC STEVENS.
